MARCUS O. ANTHONY, OF ENGLEWOOD, NEW JERSEY, ASSIGNOR TO A. KIMBALL COMPANY, OF NEW YORK, N. Y., A CORPORATION OF NEW YORK.

PIN-TICKET CARTRIDGE AND CONTAINER.

1,152,471.

Specification of Letters Patent.

Patented Sept. 7, 1915.

Application filed June 27, 1914. Serial No. 847,697.

To all whom it may concern:

Be it known that I, MARCUS O. ANTHONY, a citizen of the United States, residing at Englewood, county of Bergen, State of New Jersey, have invented an Improvement in Pin-Ticket Cartridges and Containers, of which the following description, in connection with the accompanying drawing, is a specification, like characters on the drawing representing like parts.

This invention has for its object to provide a self-contained cartridge or package comprising a series of pin tickets and a container therefor and also a novel form of container, thus enabling pin tickets to be presented in compact form for commercial purposes, and particularly in a desirable form for feeding the pin tickets to machines of various types.

20. The invention presents the pin tickets in such form that they are conveniently arranged for manual operations thereupon such as marking the pin tickets or applying the pin tickets to goods.

25. The invention presents the pin tickets in such form that they may be picked up in exactly the same way by hand without prick- ing the fingers and without necessitating turning the tickets into a desired position and at the same time the points of the pins are protected against injury during trans- portation.

30. The nature and objects of the invention will more fully appear from the accom- panying description and drawings and will be particularly pointed out in the claims.

35. The drawings illustrate a preferred form of the invention adapted to pin tickets in which the card portion is rectangular in shape.

In the drawings, Figure 1 is a perspective view of a container constructed in accordance with the invention; Fig. 2 is a sectional view taken longitudinally thereof, the pin tickets being shown in position in elevation; Fig. 3 is a sectional view taken on the line 3—3, Fig. 2, and Fig. 4 is a perspective view of the blank partially folded and ready to receive the pin tickets. Fig. 5 is a perspective view of a portion of the container showing a different form of means for securing the abutting edges; Fig. 6 is a perspective view of a portion of a container showing still another form of means for securing the abutting edges.

The invention resides both in the commercial package or cartridge comprising the arranged pin tickets and container, and also in the container itself.

The pin tickets of well known commercial form each comprises a card portion of desired shape and size herein shown for pur- poses of illustration as rectangular, and the pins herein shown as of wire secured to the ticket, and in each case presenting a pair of pins projecting from the card portion, and as shown substantially at right angles there- to. These pin tickets are arranged in series with the card portions overlapping, and the pins projecting in parallelism so that the entire series is compactly arranged and occu- pies a minimum amount of space.

The container which may be of various forms and variously constructed has as its essential requirement that it shall engage with the pin tickets to protect the pins and permit the tickets to be fed from the container in sequence as required. Preferably the engagement of the container with the pin tickets is with the card portions thereof, and of such a character as substantially to pre- vent contact of the pin points with the container itself.

In a preferred form of the invention illus- trated the container is of an elongated box- like form having a cross-section, the base portion of which is rectangular in shape and the upper portion of which is triangular or roof-shaped. In this form the proportions are such that when the tickets are arranged in series with the card portions overlapping the overlapped card portions slightly more than fill the rectangular cross-sectional area of the container, and thus are held in contact at their edges with the roof-like walls of the container so as to hold the points of the pins out of contact with the roof walls, and thus enable the pin tickets to be fed or slid out of the end of the container as required, and without the pins engaging the container.

The container is suitably closed at the ends as by bending in integral parts thereof, or by sealing up the ends so that a self-con- tainer cartridge is produced for commercial use and so that when one of the ends is broken open the pin tickets may be readily slid or fed therefrom in sequence.

In the construction illustrated the con- tainer is shown as formed from a blank of card board bent to form a flat bottom with

sides rising at right angles thereto and with the sides then again bent to converge together in roof-like form with the abutting edges secured in place and the ends of the container provided with closing means. The container may, however, vary in shape and be made of various materials suitable for the purpose, and when formed from a flat blank the meeting or abutting edges may be secured or the joint formed in any suitable manner. Three means are shown in the drawings for securing together the abutting edges. In this construction illustrated the blank 1 of cardboard or similar material presents the flat bottom 2 against which the card portions of the pin tickets lie and has integral therewith the side members or walls 4 and 5.

The pin tickets are arranged in overlapped relation with the pin points upstanding and in parallelism as indicated in Fig. 2, thus obtaining a compact relation and economy of space. The side members in the form illustrated present vertical portions 7 and 8 having extensions 9 and 10 inclined inwardly with respect to the vertical portions and meeting at their edges to form a roof-shaped cover. The meeting or abutting edges of the side portions are connected together in any suitable way to secure a rigidity of form of the container and in the construction illustrated in Figs. 1 to 4 inclusive, the result is obtained by cutting or forming inverted V-shaped notches 11 in one edge and corresponding tongues in the opposite edge so that when the edges are brought together the tongues 12 will wedge into the notches 11 and lock the edges together. The construction shown in Fig. 6 is somewhat similar excepting that the tongue 12^a is not V-shaped but is slightly larger than the notch so that when jammed into the notch locks the parts together, or paste or other adhesive may be applied to cause the tongue 12^a to adhere to the opposite wall in its notch. In the construction shown in Fig. 5 the meeting edges are secured together by pieces of paper or similar material 13 pasted or caused to adhere to the sides over the edges. The container thus constructed is of a tubular shape and of such a cross-section that the overlapped pin tickets are snugly held therein and by contact therewith are maintained in the desired similar relation.

The body of overlapped pin tickets is retained in position by engagement of the container with the pin tickets, and in the preferred construction illustrated this engagement takes place between the walls of the container and the card portions of the pin tickets in such a manner as to maintain the pin points themselves out of contact with the roof-like cover portion of the container. 60 This preferred construction is secured by

proportioning the cross-sectional area of the container to the size of the overlapped card portions so that the edges of the card portions engage with the inclined walls 9 and 10 along a line which will maintain the 70 pin points out of contact with the walls. Thus not only are the pin points protected during transportation and handling, but when the container is open the pin tickets are readily slid or fed out from the end 75 thereof.

The pin tickets are retained in the container in any convenient manner by sealing up the ends of the container. As a convenient means for this purpose portion 14 of the blank from which the container is formed may be folded inwardly at each end. These portions or flaps are of such a length and shape in the preferred form that when bent inwardly they pass over the edges of the adjacent pin ticket and engage with the sides or cover of the container as indicated at 80 15 in Fig. 1. When it is desired to remove the tickets one of these flaps may be pulled out or torn off and the box tilted to permit the tickets to slide or be fed out. The tickets may thus easily be passed into the magazine guide of a machine for marking or otherwise handling the tickets, or the cartridge 85 itself may be inserted in such a machine to 90 itself serve as a magazine from which the tickets may be fed in sequence.

The container is preferably of such a form such for example as that illustrated for a preferred form of the invention that the 100 tickets may be laid in place on the container blank and the container formed in the shape and secured by simple operations, thus providing a convenient method of assembling and packaging the pin tickets. In Fig. 4 105 the container is shown as partially folded and ready to receive the pin tickets.

The invention is not to be restricted by the particular form of container shown, as 110 various modifications are contemplated, and the invention is believed to be broadly new in providing a self-container pin ticket cartridge and a container for pin tickets constructed to retain a series of pin tickets in definite relation for the purposes indicated. 115

Having fully described my invention, what I claim as new and desire to secure by Letters Patent is:

1. A pin ticket cartridge comprising a 120 series of similarly shaped pin tickets arranged with the card portions overlapping and the pins projecting in parallelism, and a container inclosing said series and engaging the card portions thereby to hold the pins out of contact with the container, thus protecting the pin points and permitting the tickets to be fed in sequence from the container.

2. A pin ticket cartridge comprising a 125 series of similarly shaped pin tickets ar- 130

- ranged with the card portions overlapping and the pins projecting in parallelism, and a container inclosing said series having an inclined wall overlying the said pins and 5 engaging the pin tickets thereby to hold the pin tickets in compact form with the pin points projecting while permitting the tickets to be fed in sequence from the container.
- 10 3. A pin ticket cartridge comprising a series of similar pin tickets having similar rectangular shaped card portions arranged with the card portions overlapping, and the pins projecting in parallelism, and a container inclosing said series and presenting 15 roof-shaped inclosing walls, said walls engaging the edges of the overlapped card portions, thereby to hold the pins out of contact with the said walls, thus protecting 20 the pin points and permitting the tickets to be fed in sequence from the container.
4. A pin ticket cartridge comprising a series of similarly shaped pin tickets arranged with the card portions overlapping 25 and the pins projecting in parallelism, and a container inclosing said series presenting roof shaped inclosing walls engaging the edges of the overlapped card portions, and having inwardly turned end portions 30 engaging said tickets thereby holding the pins out of contact with the walls and protecting the pin points while permitting the pins to be fed in sequence from the container upon the removal of the inturned end.
- 35 5. A pin ticket cartridge comprising a series of similarly shaped pin tickets arranged with the card portions overlapping and the pins projecting in parallelism, a container inclosing said series having a bottom 40 and upwardly extending walls overlying and protecting the ends of said pins and an inwardly folded end portion retained in position by said walls and engaging the last of the series of pin tickets, 45 thereby holding the tickets from displacement and providing rigid removable means whereby the pin tickets may be fed in sequence from the container.
6. A container for holding a series of pin 50 tickets with projecting pins in definite overlapped relation comprising a blank folded to present a flat bottom with narrow vertical side portions and extensions rising therefrom and folded inwardly and meeting to 55 form a roof-shaped cover, said roof-shaped cover serving to engage the uppermost corners of the overlapped tickets to hold them in position against the bottom and also providing protection for the projecting pins, 60 the ends of the blank presenting flaps folded
- in over the ends of the pin tickets and engaging the roof-shaped cover to be retained in place thereby.
7. A container for holding a series of overlapped tickets comprising a member of 65 generally tubular shape but of a cross section to hold the tickets in definite position therein with the pins free from contact with the walls of the container and having in-folded ends engaging the end tickets to re- 70 tain them in position.
8. A container for holding a series of tickets in definite overlapped relation comprising a blank folded to present a bottom with narrow sides rising therefrom having 75 extensions forming cover portions and adapted to engage the uppermost edges of the overlapped tickets to retain them in position against the bottom, one end of said bottom being folded inwardly over the end 80 of the adjacent ticket and retained in said position by said cover portions whereby displacement of the tickets in the container is prevented.
9. A container for holding a series of pin 85 tickets with projecting pins in definite overlapped relation comprising a blank folded to present a flat bottom with narrow vertical side portions rising therefrom and having extensions bent inwardly and meeting to 90 form a cover providing room for and protecting the projecting pin points, notches formed in one of the meeting edges of the cover and coöperating locking tongues 95 formed in the other edge, the said tongues when engaged in the said notches locking the meeting edges together.
10. A container for holding a series of pin 100 tickets with projecting pins in definite overlapped relation comprising a blank folded to present a flat bottom with narrow vertical side portions rising therefrom and having extensions bent inwardly and meeting to 105 form a cover providing room for and protecting the projecting pin points, inverted V-shaped notches formed in one of the meeting edges of the cover and coöperating V-shaped tongues formed in the other meeting edge of the cover whereby when the said tongues are engaged in the said 110 notches the meeting edges are locked together.

In testimony whereof, I have signed my name to this specification, in the presence of two subscribing witnesses.

MARCUS O. ANTHONY.
